UNITED STATES PATENT OFFICE.

WILLIAM ROBERT WELKE, OF OAK CLIFF, ASSIGNOR OF ONE-HALF TO
W. J. AND C. L. BETTERTON, OF DALLAS, TEXAS.

WELL-DRILL.

SPECIFICATION forming part of Letters Patent No. 443,688, dated December 30, 1890.

Application filed May 20, 1890. Serial No. 352,556. (No model.)

To all whom it may concern:

Be it known that I, WILLIAM ROBERT WELKE, a citizen of the United States, residing at Oak Cliff, in the county of Dallas and 5 State of Texas, have invented certain new and useful Improvements in Well-Drills; and I do hereby declare the following to be a full, clear, and exact description of the invention, such as will enable others skilled in the art to which 10 it appertains to make and use the same.

My invention has relation to drills for boring and sinking Artesian and other wells; and it consists in the combination and novel arrangement of parts, as hereinafter more fully 15 described, illustrated in the accompanying drawings, and pointed out in the appended claims.

The object of my invention is, first, to provide a simple and inexpensive drill for boring Artesian and other wells, whereby a weight 20 located within a cylinder on the drill is made to force the cutters through rock, sand, and gravel met with in digging wells, and, second, to provide the drill with a set of interchangeable cutters suited for the different strata met with in sinking a well.

In the drawings, Figure 1 is a vertical section of a drill embodying my improvement. Fig. 2 is a similar view showing the cutters 30 used for drilling through rock attached to the drill. Fig. 3 is a modified form of cylinder; Fig. 4, a cross-section on the line xx of Fig. 2.

Referring to the accompanying drawings, in which like letters of reference indicate corresponding parts in all the figures, the letter A designates a metallic cylinder closed at its lower end by a head B, provided with a dependent annular flange b, at the upper edge of which and upon the outer face is formed 35 a shoulder b', against which is designed to abut a cylinder C, provided with lower cutting-edge c, and to prevent the binding of said cylinder within the well it is given a slight outward curve, as shown, and to readily 40 secure said cylinder to the head B a bolt c' is passed through suitable registering openings in the cylinder and head.

The letter D designates a head secured in any desired manner to the upper end of the

cylinder A, and is provided with a central 50 tapering opening d, through which passes the operating-rod d'.

The letter E designates a hollow weight located within the cylinder A and provided at its upper edge with an opening e, the wall of 55 which is beveled downward and inward, as shown. Upon opposite sides of the operating-rod d' and near the lower end thereof are secured in any desired manner spring-catches e', designed when the rod is lowered to enter 60 the opening e and engage with the shoulder e'' within the weight E, whereby said weight may be raised. The head D upon its lower face is cut away, as at f, to allow of the upper end of the weight, when in a raised position, to enter and allow of the spring-catches 65 to enter the tapering opening d in the head D and trip the weight.

To prevent small particles of stones, gravel, or sand entering the cylinder and prevent the 70 weight from working freely therein, I form a stuffing-box F on the head D, and to allow water and air that may be in the cylinder to escape and not interfere with the weight when descending upon the head B openings g are 75 formed in the lower end of said cylinder. When strata of sand or gravel are struck in sinking a well, the cylinder C is removed and the cylinder H placed upon the head B. This cylinder, as will be noticed, is closed at its 80 lower end by a head h, provided with a series of openings h', closed by hinged valves h''. When the cylinder is full of sand or gravel, which can be readily judged from the weight of the drill, it is raised and emptied of its 85 contents. When strata of rock are met with, the cylinders C or H are removed and cylinder I secured to the head B, which is closed at its lower end by a head i, carrying on its circumference a series of dovetailed and screw-fastened chisels or cutters i''. The method of securing these cutters to the valved head is clearly shown in Fig. 4. The head i is also provided with a series of valved openings i''', and to readily remove the contents of the cylinder 95 when brought to the surface I form therein a hand-hole i'', closed by a plate i''. To readily permit of the escape of air or water from

the upper end of the cylinder while boring, an escape-opening J is formed in the lower edge of the head B.

The operation of my improved drill, taken 5 in connection with the above description and accompanying drawings, may be briefly described as follows:

To sink a well using my improved drill proceed as follows: The proper cutters having 10 been adjusted by lowering the operating-rod which grips the weight, the rod is raised until the spring-catches enter the tapering opening in the head D and trips the weight and allows it to fall upon the head B. This operation 15 is continued until the well is of sufficient depth, and as the cylinders get full or different strata are struck the drill A is brought to the surface and cleaned, or a different set of cutters secured to the head B.

20 I do not desire to limit myself to the construction herein shown and described, as many changes may be made without departing from the spirit of my invention.

Having thus described my invention, what 25 I claim, and desire to secure by Letters Patent, is—

1. In a drill, the cylinder closed at its upper end by a head with a stuffing-box and a tapering opening and provided at its lower end 30 with suitable cutters, in combination with an operating-rod passing through the upper head and a weight, said operating-rod being provided with spring-arms adapted to engage and raise said weight within the cylinder and 35 at the top thereof automatically to release it, as and for the purpose intended, substantially as described.

2. In a drill, the combination, with a cylinder closed at its upper end by a head provided

with a stuffing-box and a tapering opening, 40 and an operating-rod with spring-arms passing therethrough, of a weight within the cylinder having its upper end shouldered to engage the spring-arms on the operating-rod and thereby be raised and automatically let 45 fall, as and for the purpose intended.

3. In a drill, the cylinder provided at its upper end with a head carrying a stuffing-box and at its lower end with a head having a dependent annular flange and cutters secured thereto, in combination with a hollow weight contained within the cylinder, and an operating-rod provided with spring-arms adapted to engage the shoulder within said weight, as and for the purpose described. 55

4. In a drill, the closed driving-cylinder containing a weight adapted to be raised by an operating-rod, in combination with a detachable auxiliary earth chamber or carrier, said earth-chamber being provided at its bottom with inwardly-opening valves and peripheral cutting members, as and for the purpose intended, substantially as described. 60

5. In a drill, the cylinder A, having head D and stuffing-box E and vents g, the weight 65 E and operating-rod d', the lower head B, having upper and lower flanges, the auxiliary cylinder I, having valved lower head with cutters, upper vent J, and side covered hand-hole i^t, all in combination, as and for the purpose set forth. 70

In testimony whereof I affix my signature in presence of two witnesses.

WILLIAM ROBERT WELKE.
